UNITED STATES PATENT OFFICE.

NICHOLAS COSSMAN, OF GREAT BEND, KANSAS.

DESIGN FOR A FRUIT-KETTLE.

SPECIFICATION forming part of Design No. 31,589, dated October 3, 1899.

Application filed August 28, 1899. Serial No. 728,794. Term of patent 14 years.

To all whom it may concern:

Be it known that I, NICHOLAS COSSMAN, a citizen of the United States, residing at Great Bend, in the county of Barton and State of Kansas, have invented and produced a new and original Design for Fruit-Kettles, of which the following is a specification, reference being had to the accompanying drawings, forming part thereof.

10 Figure I represents a front elevation view of a fruit-kettle, showing my new design. Fig. II represents a side elevation view of the same. Fig. III represents a vertical sectional view taken on the dotted line *a b* of Fig. I. 15 Fig. IV represents a plan view.

The leading or material feature of my design consists in the configuration of the lower part of the kettle. The general form of the bottom C of the kettle A is concavo-convex, 20 bellying downward. Leading from the center of the bottom outward toward its periphery is a downwardly-inclined discharge-lip B, the side walls of which flare outwardly and upwardly and the outer end of which lies 25 within a circle described by the inner walls

of the kettle A. The upper side of the bottom of the lip B inclines downwardly outward from the center of the inside of the bottom of the kettle. The legs D have their upper ends located adjacent to the outer periphery of the 30 rounded bottom C and curve from thence outwardly and downwardly, the lip B being located between two of the legs and one of the legs being located diametrically to the rear of the lip B.

35 My design is applicable to various kinds of pots, kettles, or similar articles.

Having thus described my invention, what I claim as new, and desire to secure by Letters Patent, is—

40 The design for a fruit-kettle, as herein shown and described.

In testimony whereof I have signed my name to this specification in the presence of two witnesses.

NICHOLAS COSSMAN.
